(57) **CLAIM**

The ornamental design for a brush for animals as shown and described.

DESCRIPTION

FIG. 1 is a top, front and right side perspective view of a brush for animals showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 2.

The dot-dashed lines illustrate the boundary of the enlarged view and form no part of the claimed design.
